UNITED STATES PATENT OFFICE.

MICHAEL D'INCOCNIITO, OF CHICAGO, ILLINOIS.

WIRE LOOPING AND CLINCHING MACHINE.

Application filed February 11, 1924. Serial No. 691,904.

To all whom it may concern:

Be it known that I, MICHAEL D'INCOCNIITO, a citizen of the United States, residing at Chicago, in the county of Cook and State of Illinois, have invented a certain new and useful Improvement in Wire Looping and Clinching Machines, of which the following is a full, clear, concise, and exact description, reference being had to the accompanying drawings, forming a part of this specification.

The present invention relates to a wire looping and clinching machine.

The machine has a wide variety of uses in the manufacture of staple articles constructed of wire and of wire specialties. For example, my machine has particular utility for constructing the wire frames of lamp shades, such as connecting the ribs and outer loops of the frame together. Other uses are the construction of bed springs, soap receptacles, the construction of small wire chain and myriads of other uses where a wire looping or clinching function is desired.

In the manufacture of numerous of these articles, it is frequently necessary to loop one wire around another and firmly clinch it to the second wire. This is illustrated by the clinched connection between the ribs and the hoops of a lamp shade frame, and by the connections between the main frame and the lower supporting wires of a soap receptacle. To meet this need, it has been one of principal objects of the present invention to provide a machine which will loop one wire about another and firmly clinch it thereto, the two wires being freely removable from the machine after this operation.

It is frequently desirable to loop or clinch one wire to another wire which is in the form of a small ring or eye; or to a corner or other angular formation in the second piece of wire. It has, therefore, been a further object of my invention to provide a machine which will accommodate these irregular formations in the second portion of wire around which the looping or clinching is performed.

By virtue of this, I secure the further object of being able to loop one wire within the eye or loop of another. This is illustrated by the formation of small link chain made of sections of wire having eyes looped together. It will be understood that the ma-

chine can be made to form a free loop in the first wire which is freely slideable along the second wire, or it may be made to firmly clinch the first wire to the second wire against any relative motion, depending upon the adjustment of the parts of the machine and the size of the stock employed.

A further object is to provide an inexpensive, small and compact machine, preferably one which can be easily mounted on an ordinary work bench and operated by hand or by any suitable treadle mechanism.

Referring now to the accompanying drawings wherein I have illustrated a preferred embodiment of my invention:

Fig. 1 is a side elevational view of the device mounted on a suitable bench or support, and illustrating a typical form of treadle actuating member;

Fig. 2 is a front elevational view of the same;

Fig. 3 is an enlarged vertical sectional view through the median plane of the sides and taken approximately on line 3—3 of Fig. 2, this figure illustrating the forming member at the top of its stroke;

Fig. 4 is a similar view illustrating the relation of the parts after the forming member has started its downward operative movement;

Fig. 5 is a similar view illustrating the relation of the parts upon the completion of the operating stroke of the forming member;

Fig. 6 is a vertical transverse sectional view taken approximately on the plane of line 6—6 of Fig. 3;

Figures 7, 8, 9 and 10 are sectional views taken approximately on the planes of the lines 7—7, 8—8, 9—9 and 10—10, of Fig. 3;

Fig. 11 is a fragmentary detail view of the adjustable mounting of the stop gage;

Fig. 12 is a fragmentary view similar to Fig. 4, showing a different relationship of the parts for performing a "looping" operation; and

Fig. 13 is a similar view showing how one wire is looped through the loop or eye of the other wire.

The entire machine is assembled within two side plates 15—15, which plates constitute both the frame and enclosing housing for the operating parts. As shown in Figures 1 and 2, the lower ends of these plates 15—15 have laterally projecting feet or sup-

porting flanges 16-16, which bolt at 17 to the bench or other support 18. Slots 19-19 are cut through the flanges 16, and through the support 18, to receive the two 5 operating links or bars 21-21 which extend up along the outer sides of the plates 15. Below the support 18, these bars converge together, as shown in Figure 2, and have pivotal connection through a pivot 10 bolt 22 with any suitable operating treadle 23 pivoted to a fixed support at 24. The upper ends of the links 21 pivotally connect to a bolt 25 extending transversely through the machine, the depression of the treadle 15 23 moving this bolt through an operating stroke defined by the slots 26 in the frame plates 15, through which slots the bolt 25 extends.

The stock is inserted into a tapered slot 20 27 cut into the front edge of the machine. The general formation and size of the slot is adapted to be varied in accordance with the size of stock being worked upon and upon the character of the looping or clinching 25 operation being performed, and to the end of expeditiously making the necessary adjustments for the different sizes of stock and the different formations of loop or clinch, I have notched out each frame plate 30 15 for mounting a removable die 28 which defines the slot. Each frame plate 15 carries one of these removable dies 28, the latter being releasably secured to the frame plate by a screw 29 (see Fig. 10).

It will be observed that concentrically of the inner end of the slot 27, the side wall of each plate 15 is recessed or dished out on an obtuse taper, as indicated at 31. These recesses on opposite sides of the machine permit the wire about which the looping or clinching operation is performed to be held at an angle in the slot 27; or permit the insertion of such a wire having a diagonally bent portion extending at an 40 angle to the portion about which the looping or clinching is performed; or permit the insertion of small wire rings into the slots 27 for clinching a secondary wire about such a ring. It will also be observed in 45 Fig. 1 that the frame plates 15 are cut back at their front edge directly below the slot 27, as indicated at 32. This permits of small wire rings being inserted in the slot 27 and swung downwardly into the position indicated at 33 in dotted lines for receiving the secondary wire to be looped or clinched about this ring.

As shown in Figures 3 and 4, the opposing faces of the two plates 15 are machined out to form a groove or track 35 which extends substantially vertically from the upper ends of the plates down to substantially the level of the slot 27, where this groove or track curves forwardly under 50 the slot, as indicated at 35'. The forming

member 36, which performs the looping or clinching operation, rolls in this groove under the operating impulse transmitted from the treadle 23. The slots 26, which receive the bolt 25, extend centrally of the 70 groove 35, as shown in Fig. 3. The bolt 25 is extended through an aperture in the upper end of the forming member 36, and, as shown in Fig. 6, a roller 37 is mounted on this bolt on each side of the forming 75 member 36 for tracking in the section of groove 35 formed in each of the frame plates 15. These rollers 37 project beyond the rear edge of the forming members 36 to provide a purely rolling contact of the 80 forming member in its downward motion in the groove 35. A similar pair of rollers 37' are pivotally supported at the lower end of the forming member 36 upon a pivot pin 85 38 passing through the member 36. A pair of anti-friction washers 39 are also interposed between the operating links 21 and the lateral sides of the frame plates 15 for spacing the links 21 from the plates and giving a free, sliding motion to the links. 90

The upper end of the forming member is provided with a finger 41 which normally engages between two co-operating fingers 42 and 43 on a cam 44. The opposing faces of the two frame plates 15 are each recessed to form a compartment or chamber 45 for receiving the cam 44 and its associated parts. This depression 45 extends from the right hand edge of the groove or track 35 to a point adjacent the right hand edges of the plates 15 and is of a shallower depth than the groove 35, as clearly shown in Figures 8 and 9. This depression 45 just snugly embraces the sides of the forming member 36 and the cam 44. This cam is pivoted on a pin 46 extending through the two frame plates. 100

The cam surface 47 normally bears against a cam roller 48 pivoted on a pin 49 in the end of a clamping slide 51. As shown in Fig. 7, the roller 48 is pivotally supported in the bifurcated end of the slide 51, and is of substantially the thickness of the cam 44. This leaves projecting sides on the slide 51, which engage in guide ways 52 formed as long, rectangular slots in the face of each plate 15. The lower end of the slide 51 is slotted at 53 for receiving the clamping plate 54. This plate is held in slot 53 by a pin 55. As shown in Fig. 7, the under side of the plate 54 is formed with a groove 56, which is adapted to embrace the upper half of the looping or clinching wire for firmly clamping this wire in position preliminary to the looping or clinching operation. The clamping plate 54 may be fixedly held in the slide 51 by engaging the ends of the pin 55 in closely fitting holes in the slide. As an alternative construction, the clamping plate may have a stiff clamping resiliency 115 120 125 130

by arranging the ends of the pin 55 in slots 58 and interposing a stiff spring 60 between the plate and the top of the notched recess 53 (Fig. 7).

As will be observed from Fig. 4, this clamping member 54 operates to clamp the upper wire *a*, in which the loop or clinch is formed, down against the lower wire *b*, around which the loop or clinch is formed.

10 The portion of the wire *b* around which the loop or clinch is to be formed is inserted crosswise into the slot 27 and is pushed back to the rear of the slot, where it is dropped downwardly into notches or recesses 30,

15 which hold the wire against horizontal displacement. The end of the looping wire *a* is then inserted endwise in the slot 27, directly above the wire *b*. A gage, to be hereinafter described, limits the inward insertion

20 of this wire to the proper length for forming the loop or clinch. The duty of the clamping member 54 is to force the looping wire *a* down on to the intervening span of wire *b* between the notches 30 with sufficient

25 force to firmly hold the two wires in this position during the operation of curving the end of the wire *a* down under and up against the other side of the wire *b*.

For holding the member 54 in this clamping 30 position during the operation of looping the end of the wire *a*, a notch 58' is formed at the end of the cam surface 47 for receiving the roller 48 after the clamping member 54 has been forced against the wire *a*.

35 When the roller 48 is in this notch, the line of reaction of the clamping member is through the center of the pivot 46, and the shoulder 58 being substantially square to this line of reaction, the clamping member and

40 cam are retained in this clamping position. A spring 59 is hooked at its lower end to the clamping plate 54 and at its upper end to a stationary pin 61. This spring operates to return the clamping slide to the position

45 illustrated in Fig. 3 after the completion of each looping operation, and by resiliently urging the clamping slide up against the shoulder 58, it causes the clamping slide to function as a detent for holding the cam in the position shown in Fig. 4 during the

50 looping operation.

The gage which determines the length of wire *a* inserted into the machine for forming the loop is indicated at 62, and comprises 55 a metallic bar or strap bent upwardly at its forward end to provide a front abutment surface. The other end of this bar is adjustably secured to block 63, which has pivotal mounting on a pin 64 passing between the frame plates 15.

60 The end of the bar 62 is slotted at 65, as shown in Fig. 11, and passing through this slot is a pair of screws 66 and 67, which tap into the block 63. By releasing these screws, the bar 62 can be slid forwardly or backwardly relative to

the block 63 for adjusting the setting of the gage. The gage is swung backwardly out of the way by the descent of the forming member 36, as shown in Figures 4 and 5. To accommodate the gage bar 92 and block 63, the opposing faces of the two plates 15 are recessed as shown at 68. The gage is normally held in the position indicated in full lines in Fig. 3 by a tension spring 69, which is extended between a stationary pin 71 and a wire clip 72 secured under the head of the screw 67. The spring 69 tends to draw the eye or loop in the end of the clip 72 into line with the pins 71 and 64, and thus tends to hold the gage in the full line position. The two screws 66 and 67 are accessible for adjusting the gage when the latter has been swung down to approximately the position shown in Figure 5.

The die portion of the forming member 36 comprises a forwardly extending portion 75 having an upwardly inclined lower edge 76, which terminates in a rounded toe 77.

Formed around the outer curve of the shaping toe 77 is a semicircular groove 78 (Fig. 90 3), similar to the groove 56. Beyond the toe 78 is formed a semicircular recess 79, which functions to complete the looping or clinching operation. As previously stated,

the size and shape of the slot 27 depends upon the stock being worked on. This slot is defined by the parts or dies 28 and hence to change it, the dies 28 must be changed. That is to say, for each size of stock to be bent there is a corresponding size of die 100 95 105 28.

It is, of course, obvious that the contour of the recess of groove 79 depends upon the size of stock being bent. Therefore, with each size of die 28, there is an associated forming member 36 having a recess or groove 79 adapted to cooperate with a particular size of die 28 in bending the size of stock the slot 27 of the die is built to accommodate. The forming member 36 may be easily removed from the groove 35 by separating the frame plates 15, whenever it is desired to replace it by a different size member. The operation of the machine is as follows:

The wire *b* is first inserted crosswise in the slot 27, and is dropped into the two notches 30—30 at the sides of the slot. The wire *a*, which is to be wrapped around the wire *b*, is then inserted endwise into the slot 27 until it strikes the gage 62. The treadle 23 is then depressed. From the position shown in Fig. 3, the forming member 36 is pulled downwardly through the positions shown in Figures 4 and 5. In the initial part of this downward movement,

120 the finger 41 bears downwardly on the finger 42 of the cam 44 and revolves this cam downwardly and to the right to the position shown in Fig. 4. This thrusts the clamping slide 51 downwardly, pressing the upper 125 130

wire *a* firmly down against the intervening span of wire *b* between the notches 30—30 of the slot 27. The cam 44 and slide 51 lock in the clamping position shown, by the roller 48 coming into dead-center alignment with the right angle shoulder 58', as before described.

The two wires *a* and *b* having now been firmly clamped together, the looping nose 77 10 engages the projecting end of the wire *a* and bends this wire downwardly around the wire *b* in the continued downward motion of the forming member 36. The gage 62 is, of course, displaced by contact with the lower 15 forward edge of the forming member as the latter moves downwardly. However, this gage is not displaced until the two wires are firmly clamped together by the clamping plate 54. The continued motion of the 20 forming member 36 causes this member to begin a forward movement through the arcuate portion 35' of the guiding groove or track 35. This brings the forming nose 77 forwardly so that the end of the wire *a* 25 is wrapped downwardly and around under the bottom of the wire *b*. In the last stage of the movement, the forming nose 77 is carried forwardly past the wire *b* and is then started upwardly by virtue of the upward curve in the front end of the arcuate groove 35'. This upward motion is proportioned to bring the semicircular recess 79 up under the bottom of the loop, so that the lower half of the loop will be embraced 30 in this recess, as shown in Fig. 5. The continued upward movement of the member 36, after the recess 79 has been brought into this embracing position, functions to crimp or wrap the lower part of the loop upwardly and around the under side of the 35 wire *b*.

The treadle 23 is now released, whereupon the spring 20 swings the treadle upwardly, thereby restoring the forming member 36 to its upper position illustrated in Fig. 3. In moving into this upper position, the finger 41 of the forming member 36 strikes the finger 43 of the cam 44 and kicks this cam around to bring the shoulder 58 out of register with the roller 48, whereby the spring 59 is permitted to raise the clamping slide 51. The gage 62, of course, restores itself under the tension of the spring 59. The wire *b*, with the wire *a* looped about it, is then withdrawn 45 from the slot 27 by lifting the wire *b* upwardly to clear the notches 30, and drawing the two wires outwardly through the slot. 50

It will be observed that the wire *b* serves 55 as a mandrel around which the wire *a* is wrapped. When a firm, clinched connection is desired between the two wires, the wrap wire *a* is brought around under the mandrel wire and is forced upwardly against this mandrel wire under considerable pressure to 60 solidly clinch the two wires together. This

clinching pressure may be sufficient to groove the mandrel wire *b* so as to mechanically lock the two wires together.

A comparatively loose loop, which will permit free play between the wires, can be obtained in different ways. When working with soft metal stock, a loose loop may be obtained by clinching in the ordinary manner, and then, upon removal of the two wires from the machine, turning, twisting and working the two wires so as to loosen the loop sufficiently to give the desired play. When working with harder metal or heavier gage stock it may be desirable to modify the wrapping operation by curving the wrap wire around under the mandrel wire without the application of any upward pressure to the wrap wire, so that it is not forced up against the mandrel wire, but a slight spacing is retained between the two wires. This is illustrated in Fig. 12, and may be considered a "loop" as distinguished from the "clinch" as shown in Fig. 5 and described above. This wrapping operation may be modified by employing a forming member 36 in which the forming nose 77 and recess 79 are closer to the center of the pivot pin 38; or by lowering the lower edge of the groove or guideway 35'. Another practice is to substitute the die members 28 in each frame plate 15 for die members in which the slot 27 and notch 30 are disposed at a slightly higher plane, substantially as shown in Fig. 12. In this figure, the previous depth of notch 30 for performing the clinching operation is indicated by the dotted circle *x*. It will be noticed that by raising the plane of the mandrel wire *b* and the wrap wire *a*, no clinching pressure can be applied to the wrap wire when it is curved around under the mandrel wire. Where the spring-pressed arrangement of clamping plate 54 is employed, this resiliency will accommodate the elevated positions of the wires *a* and *b*, otherwise the clamping member will, in some instances, have to be substituted.

The loop which affords play between the mandrel wire and the wrap wire is of utility in making link chain, and in numerous other situations where it is desired to have relative sliding motion of the wrap wire along the mandrel wire, or relative rotational freedom between the wires. An expeditious manner of making link chain, or for joining two wires together by inter-connected loops in my machine is to loop a wrap wire around the mandrel wire, as above described, and then withdraw the two wires and insert the loop crosswise in the slot 27, dropping it into the notches 30 and extending the wire which was previously the mandrel wire into position for looping as a wrap wire. This is illustrated in Fig. 13, from which it will be noticed that the loop of the previously looped wrap wire is disposed erect in the

slot 27 with the shank of the loop on the under side. This results in this shank portion serving as the mandrel around which the other wire is thereafter looped. For this 5 operation the notch plates 28 are preferably substituted for those having relatively high vertical slot areas 30 for permitting the upright insertion of the loop. The clamping plate 54 may be arranged to clear this 10 loop and engage the wrap wire directly behind the loop, or the clamping plate may be slotted as shown in Figs. 12 and 13 for engaging the wrap wire both forwardly and backwardly of the loop.

15 Fig. 10 illustrates one manner of mounting the plates 28 for ready removability and substitution. Each plate has a tongue portion 28' of lesser thickness than the frame plate 15, which extends back into a locking 20 recess in the frame plate. One or more screws 29 may be employed for securing this tongue to the frame plate. This permits of convenient substitution of these plates for performing the operations illustrated in 25 Figs. 12 and 13. Also, when using different sized stock, the die plate 28 in each of the frame plates 15 may be thereby substituted for dies having different sized slots 27 and notches 30, and having different degrees of 30 spacing between the inner opposing surfaces of the die plates.

Fig. 10 illustrates some of the advantages in chamfering back the frame plates 15 and die plates 38 concentric of the slot 27. 35 These chamfered depressions 31 will receive a diagonally bent or kinked wire indicated in dotted lines at 84. These recesses will also accommodate a relatively small wire ring, which can be dropped down over the 40 top of the machine and drawn into the notch 27 by virtue of these recesses. Such a ring is represented by the dash and dot lines 45 85. This ring may also be swung down into the cut-away portion 32, as indicated at 33 in Fig. 1. A section of straight stock 50 may even be inserted diagonally in the slot 27 and held therein for clinching a wrap wire around this diagonal wire at an angle.

It will be apparent that numerous modifications and rearrangements of parts may 55 be made within the metes and bounds of my invention.

I claim:

1. In combination, a frame comprising 55 a pair of plates secured together, there being a slot in the edge of the joined plates, said slot receiving a mandrel wire passing transversely of said plates, said slot having

a coextensive opening for receiving a wrap wire inserted between said plates and across 60 said mandrel wire, a clamping slide movable between said plates, guide-ways in the opposing walls of said plates for mounting said slide, said clamping slide being adapted to engage said wrap wire, a forming member 65 movable between said plates and adapted to engage the end of said wrap wire projecting into said coextensive opening, guide-ways in the opposing walls of said plates for guiding said forming member, said latter guide-ways causing said forming member to move 70 through a curved path around said mandrel wire, a cam for actuating said clamping slide, means for oscillating said cam during the initial movement of said forming member, and means for actuating said forming 75 member.

2. In combination, a frame comprising two plates secured together in abutting relation, there being a slot cut in the edges of 80 said plates transversely thereof, notches at the inner end of said slot, said slot receiving the mandrel wire, which is supported in said notches, the looping wire being inserted end-wise into said slot across said mandrel wire, 85 a clamping slide reciprocable in guide-ways in the opposing faces of said plates, a forming member movable in guide-ways in the opposing faces of said plate, said latter guide-ways being curved under said slot, 90 whereby said forming member engages the end of said looping wire and curves it downwardly and under said mandrel wire, a cam pivotally supported between said plate and operable to reciprocate said clamping slide, 95 a finger projecting from said cam, a finger projecting from said forming member and co-operating with said first named finger to oscillate said cam, actuating means, and a member connected to said forming member 100 and projecting from between said plates for connection with said actuating means.

3. In combination, means for receiving a first wire and for holding it in the position of a mandrel with respect to a second wire to be fastened thereto, means for gauging the amount of the second wire to be wrapped around the first wire, means for clamping the wires together, and forming means for operating the clamping means, 105 moving the gauging means out of its operative position and for forming the end of the second wire around the first wire.

In witness whereof, I hereunto subscribe my name this 8th day of January, 1924.

MICHAEL D'INCOGNITO.
